Inventor

UNITED STATES PATENT OFFICE

ALFRED B. FOWLER, DECEASED, LATE OF BEVERLY, MASSACHUSETTS, BY MARY F. FOWLER, ADMINISTRATRIX, OF BEVERLY, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed June 11, 1926. Serial No. 115,201.

The present invention relates to hook needle lockstitch sewing machines, and more particularly to needle thread handling devices adapted for use in such machines.

5 The object of the invention is to provide a novel and improved mechanism for supplying needle thread for the stitch forming operation, and for setting the stitch.

It is desirable in a lockstitch machine, to 10 set the stitch against a yielding resistance. Difficulty has been experienced, however, notably in cases where it has been attempted to set the stitch against a thread tension, in obtaining a regular, even stitch, because 15 of the tendency of the tension device to give up an excessive amount of thread or to overthrow. In order to eliminate this irregularity in the sewing, the stitch is usually set against a thread lock, the amount of thread 20 necessary for each succeeding stitch being carefully measured out in advance.

One feature of the present invention contemplates setting the stitch against a yielding resistance, without at the same time allowing any new thread to be drawn from 25 the supply so that any possibility of overthrow with the resulting irregularity in the stitch is eliminated.

More specifically, in the present embodiment of the invention, the stitch is set 30 against the pull-off lever which is arranged to yield against the tension of a light spring, while a relatively heavy thread tension prevents any additional thread from being drawn from the supply.

Another feature of the invention contemplates utilizing the yielding movement of 35 the pull-off lever produced by the setting of the stitch as a means for measuring automatically the varying amount of thread to 40 be pulled from the supply as the work varies in thickness.

The several features of the present invention and the advantages attained thereby 45 will be readily understood by those skilled in the art from the following description taken in connection with the accompanying drawings in which Fig. 1 is a side elevation of a McKay lockstitch horn sewing 50 machine illustrating one embodiment of the

present invention. Fig. 2 is a detailed front elevation, partly in section, showing the pull-off, take-up and thread lock. Fig. 3 is a detailed side elevation, partly in section, of the parts shown in Fig. 2 with their actuating mechanisms. Fig. 4 is a side elevation showing somewhat diagrammatically the position of the needle thread and the thread handling mechanisms as the stitch 55 is being set. Fig. 5 is a similar view of the parts illustrated in Fig. 4 after the pull-off has operated to draw new thread from the supply, and the take-up has drawn the needle loop from the shuttle partially down 60 through the work.

Except as hereinafter described, the machine illustrated in the drawings is the same in construction and mode of operation as the lockstitch McKay shoe sewing machine 70 illustrated and described in the inventor's application filed of even date herewith Serial No. 115,202. The machine is provided with a rotatable work supporting horn, a straight hook needle, a loop taker in the form of a hook for passing the loops drawn 75 up through the work by the needle over a bobbin case containing the locking thread and pull-off and take-up mechanisms for handling the needle thread.

Referring more specifically to the drawings, the horn is indicated at 6, the straight hook needle at 8, the loop taker or hook at 10, a bobbin case loosely mounted within 80 holders in the machine frame at 12, a presser foot at 14, and an awl which acts also to feed the work at 16. The machine is driven from a belt pulley 18 through a two speed clutch and driving mechanism similar to that described in the Letters Patent to Richardson No. 885,878, and controlled from the 85 foot pedal 20.

The needle thread handling mechanism which is more particularly the subject matter of the present invention, includes a take-up which acts to pull the needle loop from the shuttle partially back through the work, and a pull-off mechanism which also forms a yielding resistance against which the stitch 95 is set by the loop taker or hook. A thread lock is interposed between the take- 100

up and pull-off to cooperate with these devices and a thread tension controls the feeding of the thread from the supply to the pull-off.

- 5 The take-up mechanism comprises a take-up lever 22 carrying the two guide rolls 24 and 26 and pivotally mounted at its lower end on the shaft 28 rigidly held in the machine frame. The actuating connections for 10 the lever 22 include the cam slide 30 and a link 32 adjustably connected to the lever through the pin and slot 34. Cooperating with the guide rolls 24 and 26 on the movable lever 22 is the guide roll 36 mounted 15 on the fixed bracket 38 and the guide roll 40 mounted on the adjusting lever 42 which is fastened at its lower end to the rock shaft 44. The function of the adjusting lever 42 is to vary the action of the take-up in accordance with the thickness of the work to 20 leave always the same amount of thread above the work and reduce to a minimum the amount which must be pulled around through the work by the retracting needle. 25 The position of this lever is controlled from the presser foot bar through connections which include the lever arm 46 fastened to the rock shaft 44, connecting link 48, lever 50, link 52 and lever 54.
- 30 The thread lock which is provided to operate with the take-up and pull-off mechanisms comprises a spring pressed plunger 56 mounted in a block 58 on a bracket 60 on the machine and equipped with a rough bearing surface against which the thread is 35 pressed by the locking action of a lever 62 which carries a similar surface oppositely placed. The thread locking lever 62 is pivotally mounted on the shaft 28 and is actuated by the cam slide 64 through the connecting link 66. The thread is guided from the thread lock to the take-up rolls by means of two guiding arms one indicated at 68 being formed on the block 58 and the other indicated at 70 being bolted to the bracket 60.
- 40 The pull-off mechanism comprises a pull-off lever 72, pivoted at 74 and carrying at its lower end the roll 76 which moves between the stationary rolls 78 and 80 pivotally mounted on an arm 82 of the bracket 60. The pull-off lever has formed on its hub a small lever arm 84 which carries a roll 86 adapted to engage a projection or cam surface 88 on the hub of the take-up lever 22.
- 45 As the take-up lever is turned by the action of the cam slide 30 to take up the preceding needle loop, the projection or cam 88 is brought into contact with the roll 86 and the pull-off lever is turned about its pivot to draw new thread through the thread tension 90 from the supply.

In order that the stitch may be set against a yielding resistance, a spring 92 is inserted between a pin 94 on the pull-off lever 72 and 55 a thumb-screw 96 journaled in a plate 98

fastened to the bracket 60 so that thread will be drawn from the pull-off mechanism against the pressure of the spring in setting the stitch. The force exerted by the spring 92 is relatively smaller than the resistance in the thread tension so that the stitch is set entirely against the yielding resistance provided by the pull-off mechanism just described, without drawing more thread from the supply.

Inasmuch as no thread is permitted to escape through the thread tension from the supply during the stitch setting operation, the amount by which the pull-off lever 72 is pulled down against the tension of its spring 92 and consequently the effective throw of the lever in pulling off thread for the next stitch must vary in accordance with the thickness of the work.

In the operation of the machine, as the needle retracts through the work the thread remaining in the preceding loop is drawn around through the work and an approximately equal amount is given up by the take-up mechanism. The loop is then taken from the needle over the bobbin-case by the loop taking hook, additional thread being supplied from the pull-off mechanism against the tension of spring 92. No thread is permitted to escape through the relatively heavy thread tension 90 so that the stitch is set entirely against the yielding resistance supplied by the spring 92. The position of the pull-off lever 72 is thus finally determined in accordance with the thickness of the work before the thread lock is closed preparatory to drawing off more thread from the supply, the parts at this point in the operation being as illustrated in Fig. 4 of the drawings.

The thread lock is now closed and the take-up lever 22 caused to turn about its pivot to draw the loop from the hook 10 partially down through the work. At the same time, the projection or cam surface 88 on the hub of the take-up lever is brought into contact with the roll 86 to turn the pull-off lever 72 about its pivot and draw new thread through the thread tension 90 from the supply. Fig. 5 of the drawings illustrates diagrammatically the position of the parts at the completion of this phase in the cycle of operations.

The nature and scope of the present invention having been indicated and the preferred embodiment of the invention having been specifically described, what is claimed is:

1. A hook needle lockstitch sewing machine having, in combination, stitch forming devices, a pull-off mechanism which forms also a yielding resistance against which the stitch is set, a stitch setting device, and means for preventing thread from being pulled from the supply during the operation of the stitch setting device.

2. A lockstitch sewing machine having, in

combination, stitch forming and setting devices including a hook needle, a take-up acting to pull the needle loop from the loop taker partially back through the work, a 5 loop taker acting to set the stitch, a pull-off which forms a yielding resistance against which the stitch is set, a thread lock interposed between the pull-off and take-up, and a thread tension to prevent thread from being pulled from the supply during the 10 operation of the stitch setting devices.

3. A hook needle lockstitch sewing machine having, in combination, stitch forming devices, a stitch setting device, a pull-off 15 forming a yielding resistance against which the stitch is set, the amount of thread pulled off for the next succeeding stitch being governed in accordance with the thickness of the work by the extent of the yield, and a 20 thread tension.

4. A lockstitch sewing machine having, in combination, stitch forming devices including a hook needle acting during its retraction to draw thread from the preceding 25 needle loop, a stitch setting device, a pull-off including a yielding member against which the stitch is set, the amount of thread for the next succeeding stitch being governed in accordance with the thickness of the work 30 by the final position of the yielding member, and means for preventing thread from being pulled from the thread supply during the operation of the stitch setting device.

5. A lockstitch sewing machine having, in combination, stitch forming devices including a hook needle, a take-up acting to pull the needle loop from the loop taker partially back through the work, a loop taker acting to set the stitch, a pull-off forming a yielding 40 resistance against which the stitch is set and acting thereafter to pull off for the next succeeding stitch an amount of thread governed in accordance with the thickness of the work by the extent of the yield, a thread 45 lock interposed between the take-up and pull-off, and a thread tension acting to prevent thread from being drawn from the supply during the operation of the stitch setting device.

50 6. A lockstitch sewing machine having, in combination, stitch forming and setting devices including a hook needle and a loop taker acting to pull thread from the preceding needle loop and set the stitch of which 55 said preceding needle loop forms a part, a member against which the stitch is set arranged to yield while the stitch is being set, and means for preventing thread from being pulled from the supply during the entire 60 stitch setting operation.

In testimony whereof I have signed my name to this specification.

MARY F. FOWLER,
Administratrix of the Estate of Alfred B.
65 *Fowler, Deceased.*
